UNITED STATES PATENT OFFICE.

ARTHUR McDougall Duckham, of Ashstead, England.

DISCHARGING VERTICAL RETORTS.

1,188,255.

Specification of Letters Patent. Patented June 20, 1916.

Original application filed July 28, 1915, Serial No. 42,378. Divided and this application filed December 17, 1915. Serial No. 67,469.

To all whom it may concern:

Be it known that I, ARTHUR McDougall DUCKHAM, a subject of the King of Great Britain, residing in Ashstead, England, have 5 invented certain new and useful Improvements in Discharging Vertical Retorts, of which the following is a specification.

The present specification relates to a method of discharging through a water seal 10 a vertical retort, wherein coal or the like is continuously carbonized, and is a division from the specification of which the serial number is 42,378 of 1915.

The method, according to my invention, 15 consists in imparting a reciprocating movement to a water trough, which forms the seal, and wholly or partially supports the charge of the retort, and in completely or partially preventing the material in the 20 trough from sharing this movement in one direction, whereby some of the material leaves the trough into which fresh material descends.

Beneath the end of the retort or extension 25 thereof there is a stationary plate or the like acting as a scraper in relation to the bottom of the trough. When a reciprocating movement is imparted to a suitable mechanism the carbonized material is carried with 30 it by the movement in one direction and a free space is left between the material and the scraper into which some of the charge in the retort descends, while during the movement in the other direction the scraper 35 prevents the material from moving with the trough so that some of the material falls over the edge of the latter. By placing the scraper on a line bisecting or substantially bisecting the discharge opening of the retort or extension, the movement of the 40 trough in each direction becomes effective in discharging the carbonized material. When the scraper is flush with one side of the retort, in which case it may be an extension 45 of the side or the longer side of an obliquely cut discharge opening, the movement of the trough in one direction only is effective for discharging from the trough.

The accompanying drawing is a vertical 50 section through a water trough A into which the lower end of a retort B extends below

the water seal C. The trough A is adapted to receive reciprocating motion on the roller D and, in this example, one side B₁ of the retort B is extended to act as a stationary 55 scraper in relation to the material in the trough. When the trough is moved to the left, some of the carbonized material is discharged over the right edge of the trough, and when the trough is moved to the right 60 some of the charge falls from the retort into the trough.

Having thus described the nature of the said invention and the best means I know of carrying the same into practical effect, I 65 claim:

1. Means for discharging carbonized material from a vertical retort, comprising in combination a trough forming a water seal for the retort, means for imparting relative 70 rectilinear movement to said trough and retort, and means for preventing this movement from being fully imparted to the material in the trough.

2. Means for discharging carbonized material from a vertical retort, comprising in combination a trough forming a water seal for the retort, means for imparting a rectilinear movement to the said trough and a stationary scraper in the trough adapted to 80 prevent the movement of the trough from being fully imparted to the material therein.

3. Means for discharging carbonized material from a vertical retort, comprising in combination a trough forming a water seal for the retort, means for imparting a rectilinear reciprocating movement to the said trough and a stationary scraper secured to the vertical retort and adapted to prevent the movement of the trough from being 85 fully imparted to the material therein.

4. Means for discharging carbonized material from a vertical retort, comprising in combination a trough forming a water seal for the retort, means for imparting a reciprocating movement to the said trough, and a stationary scraper flush with one side of the discharge opening of the retort and extending across said trough.

5. Means for discharging carbonized material from a vertical retort, comprising in combination a trough to contain water, a

retort having an obliquely-cut discharge opening extending into said trough, and means for imparting a reciprocating movement to the said trough, the longer side of said obliquely cut discharge opening forming a scraper for said trough.

In testimony whereof I have signed my

name to this specification in the presence of two subscribing witnesses.

ARTHUR McDougall DUCKHAM.
